UNITED STATES PATENT OFFICE.

MARC BIRKIGT, OF BOIS COLOMBES, FRANCE.

COMBINED GUN AND ENGINE FOR AERIAL MACHINES.

1,319,510.

Specification of Letters Patent.

Patented Oct. 21, 1919.

Application filed May 31, 1917. Serial No. 172,098.

To all whom it may concern:

Be it known that I, MARC BIRKIGT, engineer, citizen of the Republic of Switzerland, residing at Bois Colombes, Department of Seine, France, have invented certain new and useful Improvements in Combined Guns and Engines for Aerial Machines, of which the following is a specification.

10 This invention relates to a combined gun and engine for aerial machines. The invention comprises a gun for use on aerial machines, in which the engine of the machine forms the gun carriage. The barrel 15 of the gun is a good sliding fit in the interior of the hollow propeller shaft, which is driven by the crank-shaft of the engine through a speed reducing device.

20 The invention further comprises a gun in which a recoil cylinder connected to the breech of the gun is secured to the casing of the engine.

25 The single figure of the drawing shows, by way of example, in axial longitudinal section an aeroplane engine on which is mounted a gun in accordance with the invention.

30 A is a fixed engine of an aeroplane driving a tractor propeller B secured to a hollow shaft a which is driven from the crank-shaft a^0 through speed reducing gear wheels b and b^0 .

35 The hollow shaft a to which is secured the tractor propeller B, is mounted in the casing A^0 of the engine A, and has at its front part ball bearings c^1 and c^2 . The casing A^0 is provided at suitable points of its length with cylindrical bearings with brasses d^1 and d^2 , the axes of which coincide with the 40 extended axis of the hollow shaft a .

45 The barrel e of the gun has cylindrical bearings e^1 and e^2 at suitable points of its outer surface, which enable the said barrel to move with a good sliding fit in the bearings d^1 and d^2 .

50 On the engine A is mounted a recoil cylinder or liquid brake f , which is connected in the known manner to the breech g of the gun projecting at the rear part of the engine A. A lubricating device h is provided to enable the liquid brake to take non-freezing oil, for example, so as to insure its good working.

Thus, it will be seen that a fixed engine

supporting a gun is obtained, the said gun 55 forming with the engine one whole, occupying the least possible space and having the smallest possible weight, which is a considerable advantage in aeroplanes in which space is comparatively restricted, the engine 60 forming an excellent carriage for the said gun and absorbing any vibrations and trepidations caused by firing, owing to the engines absorbing the effect of recoil and preventing it from being transmitted to the 65 rest of the aeroplane.

The laying of the gun is effected simply by steering the machine.

Obviously the invention is not limited to the construction described but comprises any 70 modifications within the scope of the claims.

Having now particularly described and ascertained the nature of my said invention and in what manner the same is to be performed, I declare that what I claim is:

1. The combination of an engine of an aerial machine having a casing and a tubular propeller shaft, and a gun having a barrel with a sliding mounting in the said casing and in part extending through the 80 tubular propeller shaft.

2. The combination of an engine of an aerial machine having a casing and a tubular propeller shaft, a gun having a barrel with a sliding mounting in the said casing 85 and in part extending through the tubular propeller shaft, and a recoil cylinder also mounted in a part of the casing and co-operating with the gun.

3. The combination of an engine of an 90 aerial machine having a casing and a tubular propeller shaft, a gun having a sliding mounting in the said casing and in part projecting through the said tubular propeller shaft and also provided with a rear accessible breech, and a recoil cylinder also mounted in the casing in fixed position and connected to the breech of the gun.

4. The combination of an engine of an 100 aerial machine having a casing and a tubular propeller shaft, and a gun mounted and bodily slidably in the casing and in part through the tubular propeller shaft and provided with means for controlling the recoil thereof.

5. The combination of an engine of an 105 aerial machine having a casing and a tubular propeller shaft, the casing being pro-

vided with bearings having their axes coinciding with the axis of the propeller shaft, and a gun having a sliding mounting in the said casing and propeller shaft and comprising cylindrical bearings which movably engage the said bearings of the casing.

5 In testimony whereof I have hereunto set

my hand in presence of two subscribing witnesses.

MARC BIRKIGT.
